[57] **ABSTRACT**

A switch having a bimetal latch for locking a movable spring contact in closed circuit with a second contact, and a heating coil for activating the latch to release the spring contact. A second bimetal element engages and opposes the bimetal latch and thereby counteracts the torque developed in the bimetal latch by changes in the ambient temperature.

AMBIENT COMPENSATED TIME DELAY SWITCH

This invention relates to U.S. Pat. No. 3,569,887. Its main object is to provide a more effective means of compensating for extreme changes in the ambient temperature, wherein the length of the time delay interval is adversely affected.

A further object of the present invention is to provide a delayed action switch of very simple structure, economically feasible, and one which is highly reliable under all environmental temperature conditions and durable.

The objects and advantages of this invention will become apparent from the following specification when taken in conjunction with the annexed drawing, in which,

FIG. 1 is a side view of the switch having a section of its plastic case cut away, showing the internal elements in the OFF position.

FIG. 2 is a top view with the cover and operating toggle removed.

FIG. 3 shows the relative position of the switch elements in the ON position.

FIG. 4 is a detail view illustrating the latching action of the delay device after the switch has been manually turned to the OFF position.

FIG. 5 demonstrates in another detail view the overriding position of the toggle whereby the latch is displaced and the delay interval is circumvented to instantly turn the switch off.

FIG. 6 is a detail side view of the switch elements showing the compensating action of this invention.

Referring in greater detail to the drawing, in which like numerals indicate like parts throughout the several views, the numeral 24, FIG. 1, represents a nonconductive plastic case with its side wall cut away to reveal the internal arrangement of the switch components. The case 24 supports three terminals 13, 22, and 19, in slotted openings 26, 25, and 27, respectively. Binder head screws 14, 6, and 21 provide a convenient means of attaching external circuit wires to the switch.

The terminal spring 19 bends ninety degrees at 32, and extends through the case 24 to engage the latch 34 on the bimetal blade 1. The flexible spring 19 pivots from the open circuit position shown in FIG. 1 to the closed circuit position visible in FIG. 3.

The shaft 31 of toggle 28 is cradled in the two bearings 38 in case 24, and permits said toggle to pivot from the position shown in FIG. 1 to the position illustrated in FIG. 3. A cam 29 on toggle 28 engages spring 19.

The terminal 13 is rigidly supported in the slotted opening 26 in case 24, and is riveted at 8 to a nonconductive terminal mounting block 10 within said case. The bimetal blade 1 is riveted at one end 11 to the mounting block 10, and a latch 34 is an integral part of said blade. Said latch 34 is situated in the path of movement of the end 7 on spring 19.

A coil of resistance wire 2 encircles the bimetal 1, and is connected at one end 12 to the terminal 13. The opposite end of said coil is connected to said bimetal at point 33. When end 7 engages latch 34, an electric circuit is completed from terminal 19, through coil 2, to terminal 13, and the resulting current flowing through said coil generates heat which causes the bimetal 1 to flex away from the end 7. A nonconductive sleeve 3 insulates bimetal 1 from coil 2.

A second bimetal element 15 is riveted to terminal block 10, in juxtaposition with bimetal blade 1. The free end 17 of bimetal 15 extends and is bent at 18 to engage the latch side of bimetal blade 1. The purpose of the bimetal element 15 will be detailed in the final paragraphs of this specification.

A cover plate, or mounting yoke 30 is shown, FIG. 1, having conventional mounting ends 35, for installation in standard wall receptacle boxes.

To turn the switch on, the toggle 28 is manually moved from the OFF position shown in FIG. 1 to the ON position of FIG. 3. Movement of said toggle to the ON position rotates cam 29 against spring 19, forcing said spring downward, thereby causing extension 16 to electrically engage contact which is riveted at 5 to mounting block 10. Contact 23 is electrically connected to terminal 22 (via means not shown) to complete an electric circuit between terminal spring 19 and terminal 22. As spring 19 moves to the closed circuit position, end 7 traverses the angular surface 4 on latch 34 and displaces said latch from the path of movement of said end. When the spring 19 reaches its fully closed position, FIG. 3, the bimetal 1 springs back to its normal position and places latch 34 in the return path of movement of end 7. In the fully ON position of FIG. 3, cam 29 holds spring 19 down far enough so that the end 7 does not engage latch 34.

To turn the switch off, the toggle 28 is manually moved to the OFF position visible in FIG. 1. Cam 29 is thereby rotated away from spring 19, permitting said spring to pivot upward far enough to bring end 7 into engagement with latch 34. Electrical continuity is established between terminal 19 and terminal 13 via engagement of end 7 with latch 34, causing current to flow through coil 2. The bimetal blade 1 flexes away from end 7 as a result of heat generated by the current flowing through coil 2. A sliding contact is maintained between end 7 and latch 34 as said latch is drawn away from the end 7 by the flexing of blade 1. When sufficient heat has been generated to flex the bimetal 1 to the position shown in FIG. 5, the spring 19 will be released by latch 34 and will return to the open circuit position of FIG. 1. An interval of time lapses between the instant when the toggle 28 is manually moved to the OFF position and the instant when spring 19 is released by latch 34. The length of the delay interval is determined by the time required for coil 2 to generate the necessary heat for flexing the bimetal blade 1 sufficiently to remove the latch 34 from the return path of movement of end 7.

Another factor, however, imposes an undesirable effect upon the length of the delay interval: the constantly changing ambient temperature. When the surrounding temperature decreases, the bimetal blade 1, if not restrained, will flex toward the end 7, and if it is restrained from motion, it will build up force in the direction of end 7 as a result of the temperature drop.

The adverse flexure, or force build up, must first be counteracted, or overcome, before the desired directional motion can be obtained whereby the switch is actuated. Consequently, when the switch is functioning in a below normal temperature environment, the heat generated by coil 2 must first overcome the adverse torque already existing in blade 1 before its normal function begins.

To cancel the effect of this adverse flexure, a second bimetal element 15 is rigidly fixed to the terminal base 10 at one end 36, and is oriented so that its temperature responsive flexure opposes that of bimetal 1. The free end of bimetal 15 is bent 17 to extend toward the free end 41 of blade 1. The extreme end 18 of bimetal 15 bends around and engages the free end of blade 1. A simultaneous increase or decrease in the temperature of both bimetal 15 and bimetal 1 causes the two to flex in opposite directions. Therefore, when the surrounding temperature falls below a relatively normal condition, the resulting opposite motion of the two units causes end 41 and end 18 to engage. A continued decrease in their common temperature will serve to build up force in both bimetal units, each one exerting its force against the other, and each unit thereby restraining the other against motion. The counteracting force of each bimetal unit against the other, due to the engagement of end 41 with end 18, neutralizes the pulling force that otherwise would cause the two ends of the respective bimetal units to flex away from each other.

In order to visualize the ambient temperature compensating action of this invention, let us assume that the environmental temperature is thirty degrees below zero F. When the toggle 28 is rotated to the OFF position, FIG. 4, the end 7 of spring 19 engages latch 34, thereby energizing the coil 2. Because of the opposing stresses already developed in bimetal 1 and bimetal 15 by the extremely cold environment, end 18 and end 41 will be firmly pressed together. The heat produced in bimetal 1 by the current flowing in coil 2 immediately begins to neutralize the torque existing in blade 1. No heat, however, is generated in bimetal 15. The counteracting pull of bimetal 15 is therefore still present, and continues to exert itself against bimetal 1. The heat generated by coil 2 functions to flex bimetal 1 and latch 34 in a direction to release end 7, while the low ambient temperature causes bimetal 15 to flex in the same direction. The continued pulling force of bimetal 15 against bimetal 1, coupled with the heat flexure of bimetal 1, results in the two bimetal units bending in the same direction as shown in FIG. 6, thereby releasing end 7 to return to the open circuit position. A heat shielding sleeve 20 isolates bimetal 15 from the heat produced in coil 2.

The delay period may be avoided and the switch may be instantly turned off if desired. To accomplish this the toggle 28 must be manually moved to the overriding position shown in FIG. 5. The projection 9 is shown in this view engaging the latch 34. Rotation of toggle 28 to this position swings the projection 9 against latch 34 and forces bimetal blade 1 away from the end 7 of spring 18, and thereby releases the spring 19 to return to the open circuit position.

The variables bearing upon the action of this device include the torque required in the blade 1 to overcome the frictional load imposed upon it by the engagement of end 7 against latch 34, the required heat in coil 2 to produce the flexure of bimetal 1, and the torque required in bimetal 15 to perform its compensating

pulling action against bimetal blade 1. It will be obvious to anyone skilled in the art of bimetal design that a variety of combination in bimetal types and configurations, as well as the manner of coupling the opposing forces together, may be employed to perform the compensating action described and claimed herein.

I claim:

1. A switch mechanism comprising: support means, fixed and movable contact means secured relative to said support means, an operator means secured relative to said support means and having a first position wherein said operator means causes said contact means to engage each other, and latch means which hold said contact means in engagement with each other for a predetermined interval of time after said operator means is moved from said first position to a second position out of engagement with said movable contact means, said latch means being thermally responsive and having heat generating means, ambient temperature responsive means secured to said support means in space relation to said latch means and engaging said latch means to counteract the adverse torque developed in said latch means by changes in the ambient temperature, said heat generating means being energized when said operator means is moved from said first position to said second position to move said latch means out of engagement with said contact means whereby said contact means disengage.

2. A switch mechanism comprising: support means, fixed and movable contact means secured relative to said support means, an operator means secured relative to said support means and having a first position wherein said operator means causes said contact means to engage each other, and latch means which hold said contact means in engagement with each other for a predetermined interval of time after said operator means is moved from said first position to said second position out of engagement with said movable contact means, said latch means including a bimetal blade secured at one of its two ends to said support means and having heat generating means, a second bimetal element secured to said support means in space relation to said bimetal blade and oriented so that its ambient temperature responsive flexure engages and opposes that of said bimetal blade and thereby counteracts the adverse forces developed in said bimetal blade by changes in the ambient temperature, said heat generating means being energized when said operator means is moved from said first position to said second position to move said latch means out of engagement with said contact means whereby said contact means disengage.

3. The switch as set forth in claim 1 wherein said operator means has a third position, said second position being between said first position and said third position, said operator means engaging said latch means when said operator means is in said third position to displace said latch means from the path of movement of said movable contact means to permit said contact means to return to the open circuit position without the delay interval.
